Primary Examiner—James Gandy*Assistant Examiner*—Cathron B. Matta*Attorney, Agent, or Firm*—Majestic, Parsons, Siebert & Hsue**[57] CLAIM**

The ornamental design for a container lid, as shown and described.

DESCRIPTION

FIG. 1 is a front elevational view of the container lid showing my new design wherein the broken lines of the container and the straw are for illustrative purposes only and form no part of the claimed design;

FIG. 2 is a top plan view thereof wherein the rearmost portion of the lid, as defined by FIG. 1, appears at the lowermost portion of FIG. 2, showing a pop-up portion in an unextended position;

FIG. 3 is a top plan view thereof wherein the rearmost portion of the lid, as defined by FIG. 1, appears at the lowermost portion of FIG. 3, showing the pop-up portion in an extended portion;

FIG. 4 is a rear elevational view thereof;

FIG. 5 is a front elevational view thereof, absent the merely illustrative broken lines of FIG. 1;

FIG. 6 is a left side elevational view thereof;

FIG. 7 is a right side elevational view thereof; and,

FIG. 8 is a top perspective view thereof.
